UNITED STATES PATENT OFFICE.

GEORGES HURET, OF PARIS, FRANCE, ASSIGNOR TO SOCIETE ANONYME JEAN PATOU, OF PARIS, FRANCE.

DESIGN FOR A POWDER BOX.

Application filed May 23, 1927. Serial No. 22,131. Term of patent 3½ years.

To all whom it may concern:

Be it known that I, GEORGES HURET, a citizen of the Republic of France, residing at Paris, France, have invented a new, original, and ornamental Design for Powder Box, of which the following is a specification, reference being had to the accompanying drawing forming a part thereof.

In the drawing the figure is a perspective view of a powder box showing my new design.

I claim:

The ornamental design for a powder box substantially as shown.

GEORGES HURET.
